IRONING TABLE

Application filed May 27, 1929. Serial No. 366,429.

This invention relates to ironing tables and particularly to ironing tables of the collapsible type wherein the legs may be folded against the board when the table is not in use.

The main objects of this invention are to provide a collapsible ironing table having improved means for connecting the end legs to the board so as to cause their free ends 10 to diverge when the legs are shifted into a position transverse to the board; to provide a three legged collapsible table of this kind having an improved form of brace for bracing the forward end of the board against 15 the third leg structure; to provide improved means controlled by the third leg structure for shifting the rear legs into and out of operative position; and to provide an ironing table of this kind having an improved 20 form and arrangement of parts adapted to occupy a small amount of space when collapsed and adapted to form a rigid structure when the table is set up.

An illustrative embodiment of this invention is shown in the accompanying drawings, wherein:

Figure 1 is a perspective of an improved ironing table showing the braces partially collapsed preparatory to folding the legs 30 against the board.

Fig. 2 is a side elevation of the table in set up position.

Fig. 3 is a bottom plan of the table collapsed.

Fig. 4 is a side elevation of the collapsed table.

Fig. 5 is an end elevation of the table, taken from the left of Fig. 2.

Fig. 6 is an enlarged detail in elevation 40 showing the connection between the board and the legs.

Fig. 7 is an enlarged perspective of one of the brackets for connecting the board to the legs.

Fig. 8 is a perspective of the board 45 and the legs.

The present invention may be applied to various types of tables but, in the specific embodiment herein shown, it is applied to a collapsible ironing table.

In ironing tables of the three-legged type, 50 it is desirable that the two rear legs diverge

downwardly when the table is set up, so as to give the supporting structure the necessary rigidity which will secure the table against accidental tipping. However, when the table is collapsed, the supporting structure should be compact and, therefore, the ends of the legs should be movable to positions within the side edges of the board. 55

In some instances double hinge connections have been employed for connecting the board to the rear legs so as to cause the legs to spread apart when set up and to converge when the table was collapsed. The principal objection to such constructions was the high cost of manufacture. In certain other devices, the hinges were constructed to permit the legs to rock laterally on their pivotal axes. Such other devices were objectionable because a considerable amount of bracing was necessary to secure the legs 60 against wobbling when the table was set up. 65

The improved table to which this invention is applied includes the usual top or board on which the rear legs are hinged on fixed axes which are inclined with respect 70 to the plane of the board. The axes of hinges are disposed in angular relation to each other so as to cause the legs to spread when the table is set up and to assume substantially parallel positions when collapsed. 75 The rear legs and third leg structure are braced by improved braces connected to the board so as to form a very rigid structure. 80

In the form shown, the improved table comprises a board 1, having secured to its lower face adjacent one end thereof, a pair 85 of brackets 2, to which is pivoted a pair of rear legs 3 and a third leg structure 4.

The board 1 is of the usual form employed for ironing use. 90

The brackets 2 are of right and left hand construction and each comprises a bearing part 5 having an aperture 6 for receiving a hinge rod 7 to which the third leg structure 4 is pivoted. Integrally formed on the bearing part 5, is a pair of lugs 8 and 9 having apertures 10 for receiving bolts 11 by which the brackets are secured to the board 1. Located between the lugs 8 and 9, is a recess 12 to permit the bracket to embrace a batten 95 100

13, which extends transversely across the lower face of the board.

5 Integrally formed on the brackets 2 adjacent the lugs 8, are lugs 14, to which the rear legs 3 are hinged by pins 15. The two lugs 14 diverge downwardly and the pins 15 converge downwardly so as to cause the legs 3 to spread when the table is set up, as illustrated in Figs. 1 and 5, and to assume substantially parallel positions when the 10 table is collapsed, as shown in Fig. 3.

15 Connected to the rear legs 3, adjacent the lower ends thereof, is a toggle 16, which is connected to a diagonal brace 17 comprising a pair of sections 18 and 19. The inner ends 20 of the sections 18 and 19 are hinged together by a hinge 20. The lower end of the section 18 is hinged to the toggle 16 and the upper end of the section 19 is hinged to a pair of spaced guide rails 21 secured to the lower face of the board 1.

25 In the form shown, the third leg structure 4 comprises a pair of sections 22 connected together at their lower ends and hinged at their upper ends to the pin 7. The sections 30 22 are spaced apart at their central and upper portions and slidably embrace the diagonal brace 17. Secured to the leg sections 22, is a pair of cross strips 23, which are positioned to slidably engage respectively opposite sides of the brace section 19 so that, when the diagonal leg 4 is swung relative to the board 1, the brace 17 is automatically collapsed or extended.

35 In the construction illustrated, an improved brace 24 extends between the leg 4 and the board 1. The brace 24 comprises a pair of sections 25 and 26 having their outer ends pivotally connected to the leg 4 and 40 guide rails 21 by pins 27 and 28 respectively, and having their inner ends hinged together by a hinge 29. When the brace 24 is extended, as shown in Fig. 2, the inner extremities of the sections 25 and 26 abut each 45 other in alignment with the pivots 27 and 28 and the axis of the hinge 29 is then offset from the plane of these pivots, so that the brace 24 is secured against accidental collapse without the use of the clamps heretofore employed.

50 In operation, when the table is collapsed, the parts occupy the positions shown in Figs. 3 and 4. To set up the table, the operator drops the outer end of the leg 4 and 55 extends the brace 24 by moving one of the sections 25 or 26 outwardly. By extending the brace 24, the leg 4 is forced to operative position and the top strip 23 extends the brace 17 so as to shift the rear legs 3 into operative position.

60 To collapse the table, the brace 24 is first collapsed, thereby moving the leg 4 inwardly and automatically collapsing the diagonal brace 17 which draws the rear legs 3 toward 65 the board.

Although but one specific embodiment of this invention has been herein shown and described, it will be understood that numerous details of the construction shown may be altered or omitted without departing 70 from the spirit of this invention as defined by the following claims.

We claim:

1. A collapsible table comprising a top, a batten extending transversely across the lower face of said top adjacent one end thereof, a pair of brackets secured to said top, the top face of each of said brackets being recessed to receive said batten, said brackets comprising depending bearing members having apertures therein, a hinge pin supported in said apertures, a diagonal leg structure hinged on said pin, a pair of lugs integrally formed on said brackets and diverging downwardly, and a pair of rear legs hinged on said lugs on fixed axes converging downwardly, the axes of said rear legs being offset from the axis of said hinge pin longitudinally of the table top. 80

2. In a collapsible table, a top, a pair of rear legs hinged to said top, a toggle connected to said rear legs for shifting the lower ends of said legs toward and from each other, a diagonal leg hinged to said top, a diagonal brace comprising a pair of sections having their inner ends hinged together and having their outer ends hinged respectively to said top and to said toggle, a pair of shoulders mounted on said diagonal leg in position to engage respectively opposite sides of one of said brace sections whereby said 100 brace and toggle are collapsed and extended by the movement of said diagonal leg relative to said top, and another brace comprising a pair of sections hinged together and having their outer ends hinged respectively to said top and said diagonal leg, the hinge connections between said top and said braces being spaced apart longitudinally of said top. 105

Signed at Portland, this 20th day of May, 110
1929.
